UNITED STATES PATENT OFFICE.

JOHN O. CARREY, OF ST. LOUIS, MISSOURI, ASSIGNEE TO CARREY-MORSE ENGINEERING COMPANY, OF ST. LOUIS, MISSOURI, A CORPORATION OF MISSOURI.

MULTIPLE FLYWHEEL AND CENTRIFUGAL CLUTCHING MECHANISM THEREFOR.

Application filed September 20, 1926. Serial No. 136,553.

This invention relates to new and useful improvements in multiple fly wheels and clutching mechanism of the type disclosed in my copending applications Serial No. 57,138 filed September 18, 1925, and Serial No. 124,348, filed July 28, 1926. Application Serial No. 57,138 has matured into Patent No. 1,689,913, granted October 30, 1928.

In this type of mechanism a pair of fly wheel members is coaxially mounted adjacent to each other in normally disengaged relation with each other and said fly wheel mechanism being adapted to be interengaged when one of said fly wheel members reaches a predetermined speed. Thus said fly wheels are brought into operation successively, thereby relieving the motor of excessive load during the starting operation and allowing it to reach its normal speed in much shorter time.

The objects of the present invention are to generally improve upon and simplify the construction of multiple fly wheels and clutching mechanism thereof and to so construct and arrange the cooperating fly wheel members as to insure efficient circulation of air therethrough and prevent undue heating of the device.

Further objects of the invention are to provide a pair of arms for controlling the centrifugal movement of the main levers in order to prevent untimely operation of the latter, said arms being operable at predetermined speeds and having operative connections with each other to effect simultaneous and uniform operating movement of both of said arms.

Still other objects of the invention are to provide a device of the class described which is economical to manufacture, contains but few parts, and can be readily assembled and disassembled.

With these and other objects in view, my invention consists in certain novel features of construction and arrangement of parts, hereinafter more fully described and claimed, and illustrated in the accompanying drawings, in which—

Figure 1 is a front elevational view of one of the fly wheel members and showing the other one in cross section.

Figure 2 is a horizontal cross section taken on line 2—2 of Figure 1.

Figure 3 is a fragmental elevational view showing the arms in disengaged position.

Figure 4 is a detail cross section taken on line 4—4 of Figure 1.

Figure 5 is a detail cross section taken on line 5—5 of Figure 1.

Figure 6 is an elevational view of the device illustrating the relative disposition of the spokes of the respective members.

Figure 7 is a detail cross section taken on line 7—7 of Figure 6.

In the operation of fly wheel devices of the type disclosed in the above-mentioned applications, it was found desirable to hold the weighted levers positively in retracted positions until a predetermined speed was reached in order to prevent said levers from moving into engaging positions prematurely and before the proper speed was reached. This premature movement of the levers would bring the friction elements into engagement with the stationary fly wheel member and cause said elements to drag or rub against the latter, thereby exerting braking action against the revoluble member and retarding the operation of the latter. Consequently the revoluble member would not be able to reach, or would be greatly retarded before reaching, the proper speed necessary to obtain positive interengagement between the two fly wheel members. To eliminate these objectionable features, I provide simple means for releasing the weighted levers at predetermined speeds, said means being equalized in their movements so as to release both of said levers at the same time.

Referring by numerals to the accompanying drawings, 10 indicates a driving fly wheel member having a tubular hub portion 11 from which extend radial spokes 12 forming a support for rim portion 14 of said fly wheel member. The driving member 10 may be actuated in any suitable manner, in the present instance being set in operation by means of a belt 15 which operates over the peripheral face of rim 14. A driven fly wheel member 16 is provided with a hub portion 17 which extends into the hub portion 11 of member 10. Spokes 18 extend from hub 17 and terminate in a rim 19 which is concentrically disposed with rim 14 and is spaced inwardly therefrom as shown in Figures 1 and 2. Said rim 14 is offset to one side with respect to spokes 12 so as to provide clearance for the reception of rim 19 which is narrower than rim 14 so that when driven fly wheel member 16 is placed in position, it

is disposed flush with the edge of rim 14. Driven fly wheel member 16 is preferably mounted on a shaft 20, being secured in any suitable manner to shaft 20 of the device 5 which it is desired to operate. Thus said shaft forms a support for the concentrically arranged fly wheel sections 10 and 16.

Pivottally mounted on the driving member 10 as indicated at 21 is a pair of segmental 10 friction elements 22 which are spaced a suitable distance from rim 14 and are adapted when moved into expanded positions to engage the inner face of rim 19 and connect the driven member 16 with said driving member 15. These segmental friction members are operated by means of levers 24 pivotally mounted at 25 on certain of the spokes 12 and each is provided at its short end with a tooth 26 which enters a notch 27 formed 20 in the free end of a corresponding friction element 22. Each lever 24 is weighted as indicated at 28 and is adapted to move by centrifugal force outwardly when member 10 is actuated, thereby bringing the corresponding friction element 22 outwardly into engagement with rim 19 of driven member 16.

In order to prevent untimely operation of levers 24, a pair of control arms 29 is 30 provided, each of which has a shoulder 30 which, when said levers and said arms occupy retracted positions, lies in the path of movement of the free end 29^a of its respective lever 24 so that the latter cannot move outwardly so long as arms 29 occupy retracted positions. Each arm 29 is pivotally mounted at the opposite end and the pivot point is preferably located on one of the levers 24 as indicated at 31 in order to lessen the manufacturing costs and expedite the assembling operations. This pivotal interengagement of lever 24 and arm 29 is accomplished by slotting the laterally presented flange 24^b of each lever 24 as indicated at 32 and reducing a portion of the end 29^a so as to provide a comparatively narrow neck portion 33 which traverses the corresponding slot 32, there being sufficient clearance provided between portion 33 and slot 32 to permit pivotal movement of arm 29.

To prevent upward movement or accidental displacement of each arm 29, the lower portion of slot 32 is undercut inwardly or toward the center as indicated at 32^a so as 55 to provide a lip or shoulder 34 which overhangs the portion 33 and holds said arm against withdrawal from said slot. A coil spring 35 is connected at one end to one of the arms 29 at a suitable point and at the 60 opposite end to the opposite lever 24 near the free end thereof, the tendency of each spring being to hold the interengaged ends of each lever 24 and arm 29 in retracted or closed positions. In order to insure simultaneous and uniform operation of arms 29

so that both levers 24 will be released at the same time, each of said arms 29 has pivotally connected thereto one end of a link member 36, the opposite end of which is pivotally connected to a member 37, which, in the present instance, is in the form of a ring loosely arranged on the hub portion 11 of the driving member. By this arrangement it is not necessary to provide accurate adjustment of arms 29 as the outward movement of one of said arms will, through link connections 36 and member 37, set in operation the opposite arm so that both of the levers 24 will be released simultaneously. Levers 24 are preferably made of angle iron of proper size, cut to proper shape, and the levers 24 as well as arms 29 are case-hardened so as to insure long wear of the mechanism.

Means for attaching the springs to the respective levers and arms consists preferably of cotter pins 38 seated in the apertures of the respective members.

In the operation of fly wheels, as for instance when used in combination with domestic refrigerating apparatus, it is desirable to provide circulation of air in a definite direction. To this purpose I form the spokes 12 and 18 in the form of blades or vanes as indicated in Figure 7 disposed at a definite angle so as to force the air in the proper direction.

If the two fly wheel members were formed with equal number of spokes, it might happen that said members would become interengaged with the spokes of one member positioned intermediate the spokes of the other member so that the air spaces between the spokes of each member would be blocked by the spokes of the other member, and the circulation of air would be thereby considerably impaired. To guard against such contingency, I space the spokes of one member unevenly with regard to the spokes of the other member, in the present instance, the driving member 10 being formed with four spokes and the driven member with five spokes, as clearly shown in Figure 6, so that at no time can the spaces between the spokes of one member be completely blocked by the spokes of the other member.

The provision of control or auxiliary arms 29 insures the operative movement of frictional elements 22 at a speed greater than that necessary to operate said elements whereby the latter are positively moved into engagement with the driven member 16 thereby preventing slowing down of the driving member and accidental slippage of the frictional elements with respect to the driven member.

In this manner a fly wheel is provided having the requisite mass necessary to obtain the desired momentum. However, the prime mover is not required during the

starting operation to overcome the inertia of the total mass as the fly wheel being made in sections, only the first section is set in operation when the motor is started, the other section or sections being set in operation successively after the motor and the first fly wheel section have attained the proper speed. The motor is not placed under excessive load during the starting operation, thereby enabling it to reach normal speed in a comparatively short time, at the same time prolonging the life of the motor and reducing the consumption of the current during the starting operation. After the motor and first section have reached proper speed the clutching in of the next section does not retard the speed of the motor in the first section very materially as the momentum of the first section assists the motor during the clutching in of the next section.

The clutching in of the second or successive section is timed so as to take place after the motor and the driving section have reached normal speed and the fall of the speed incidental to the clutching in of the second section is not great enough to affect the centrifugal force by which the friction elements 22 are moved into engagement with the driven section. Consequently, there is no slippage of said friction elements and the fly wheel sections are operatively interengaged. Fly wheel construction is particularly desired in devices which are frequently started and stopped, such as domestic refrigerating apparatus, air compressors and other devices.

It is to be understood that various modifications and changes in the construction and arrangement of my device can be made and substituted for those herein shown and illustrated without departing from the spirit of my invention.

I claim:

1. A sectional fly wheel comprising two coaxially arranged fly wheel members revoluble independently of each other, one of said members being a driving member and the other a driven member, segmental members movably carried by said driving member and frictionally engageable with said driven member, centrifugal arms pivotally carried by said driving member and in engagement with said segmental members for actuating same, centrifugally operable control arms pivotally mounted on said centrifugal arms for normally engaging and locking the opposite centrifugal arm in retracted positions and operable to release the latter at a higher rate of speed than that necessary to operate said centrifugal arms, a disk loosely mounted coaxially with said fly wheel members, a link connecting each control arm with said disk for effecting simultaneous operation of said control arms, and springs connected to the interlocking

arms for retracting said centrifugal arms and said control arms.

2. A sectional fly wheel comprising coaxial fly wheel members normally revoluble independently of each other, one of said members being a driving member and the other a driven member, centrifugally operable means carried by said driving member and operable to engage said driven member and interengage it with said driving member, centrifugally operable control arms pivotally mounted on said centrifugal means and adapted to normally hold the latter in retracted positions and operable to release said centrifugal means when said driving member reaches a predetermined speed, at which speed said centrifugal means are brought into operative engagement with said driven member, and coiled springs connected at their ends to said centrifugal means and said control arms respectively for simultaneously retracting said centrifugal means and said control arms at predetermined low speeds.

3. A sectional fly wheel comprising a driving fly wheel member and a driven fly wheel member arranged in cooperative relation and normally revoluble independently of each other, each of said fly wheel members having its spokes arranged in a definite relation with the spokes of the other member so as to prevent blocking of the spoke spaces of one member by the spokes of the other member, friction elements pivotally mounted on said driving member and operable to engage said driven member and interengage said fly wheel members together, weighted levers pivotally mounted on said driving member for actuating said friction elements, and auxiliary arms pivotally carried by said driving member and engaging the free ends of said weighted levers so as to lock the latter against operating movements, said arms being operable by centrifugal action to release said levers at a speed greater than that necessary to operate the latter, thereby storing energy in said weighted levers to insure efficient operation of said friction elements.

4. A sectional fly wheel comprising a driving fly wheel member and a driven fly wheel member coaxially arranged, said driven fly wheel member having an annular flange presented against said driving member and said driving member being normally revoluble independently of said driven member, a pair of frictional segments movably mounted on said driving member and operable into engagement with the flange of said driven member, a pair of weighted levers pivotally mounted on said driving member and having one of their ends in operative engagement with said segments to actuate the same, said levers being operable by centrifugal action to effect interengagement of said

- segments with said annular flange, a pair of control arms pivotally carried by said driving member and having their free ends disposed at right angles to the free ends of said weighted levers and adapted to engage the latter and hold said levers in retracted positions, whereby said weighted levers are prevented from actuating said segments as long as said control arms occupy retracted 60 positions, said control arms being operable by centrifugal action at differential speed with respect to the speed necessary to operate said weighted levers and yielding means for bringing said weighted levers and said 10 control arms into retracted positions and into interengagement with each other when the speed of the device falls below a predetermined rate.
5. A sectional fly wheel comprising a driving fly wheel member and a driven fly wheel member coaxially arranged, said driven fly wheel member having an annular flange presented against said driving member and said driving member being normally revoluble 20 independently of said driven member, a pair of frictional segments movably mounted on said driving member and operable into engagement with the flange of said driven member, a pair of weighted levers pivotally 25 mounted on said driving member and having one of their ends in operative engagement with said segments to actuate the same, said levers being operable by centrifugal action to effect interengagement of said segments with said annular flange, a pair of control arms pivotally carried by said driving member and having their free ends disposed at right angles to the free ends of said weighted levers and adapted to engage the latter and hold said levers in retracted positions, whereby said weighted levers are prevented from actuating said segments as long as said control arms occupy retracted 30 positions, said control arms being operable by centrifugal action at differential speed with respect to the speed necessary to operate said weighted levers and yielding means for bringing said weighted levers and said control arms into retracted positions and into interengagement with each other when the speed of the device falls below a predetermined rate, and means for interengaging said control arms and effecting simultaneous and uniform operation thereof.
- 55 6. In a device of the class described, a shaft, a driven fly wheel member fixed to said shaft and provided with a laterally presented annular flange, a driving fly wheel member loosely arranged on said shaft and provided with an annular flange overhanging the flange of said driven member, a pair of frictional segments pivotally mounted at one of their ends on said driving member and adapted to engage the inner face of the flange of said driven member, a pair of 65 weighted levers pivotally mounted on said driving member and having one of their ends in operative engagement with the free ends of said frictional segments, whereby when said levers are actuated by centrifugal action said frictional segments are brought into engagement with said driven member, a pair of control arms pivotally carried by said driving member and arranged at substantially right angles to said weighted 70 levers with the free ends of said control arms engaging the free ends of said levers and holding the latter in normally retracted positions, coiled springs connected at their ends to the respective control arms and weighted levers for maintaining the same in retracted positions, said control arms being operable at differential speed with respect to said weighted levers to insure efficient engagement of the friction segments with the 75 driven member upon the release of said weighted arms, and a pair of links movable simultaneously in opposite directions and pivotally connected to said control arms for insuring simultaneous operation thereof.
7. In a device of the class described, the combination of a shaft, a fly wheel driven member fixed to said shaft and provided with a hub extension, a fly wheel driving member loosely mounted on said hub extension, said driven fly wheel member being provided with a rim presented laterally towards the driving member and spaced inwardly from the rim of the latter, a pair of segments movably mounted on said driving member and operable to engage the rim of said driven member and lock said fly wheel members together, a pair of weighted levers pivotally mounted on said driving member and having one of their ends in operative engagement with said segments for actuating same, a pair of control arms each of which is pivotally mounted at one end on one of said levers and has its opposite end engaging the free end of the other lever, and a coiled spring for yieldingly connecting the interengaged control arm and lever with each other and holding them in retracted positions, said control arms being operable at a higher rate of speed than that necessary to actuate said weighted levers, thereby effecting the release of said weighted levers after the speed necessary to operate said levers has been passed so that the segments are positively moved into engagement with the driven fly wheel member.
8. In a device of the class described, the combination of a shaft, a fly wheel driven member fixed to said shaft and provided with a hub extension, a fly wheel driving member loosely mounted on said hub extension, said driven fly wheel member being provided with a rim presented laterally towards the driving member and spaced inwardly from the rim of the latter, a pair 125

- of segments movably mounted on said driving member and operable to engage the rim of said driven member and engage said fly wheel members together, a pair of weighted levers pivotally mounted on said driving member and having one of their ends in operative engagement with said segments for actuating same, a pair of control arms each of which is pivotally mounted at one end 5 on one of said levers and has its opposite end engaging the free end of the other lever, and a coiled spring for yieldingly connecting the interengaged control arm and lever with each other and holding them in retracted positions, said control arms being operable at a higher rate of speed than that necessary to actuate said weighted levers, thereby effecting the release of said weighted levers after the speed necessary to operate 10 said levers has been passed so that the segments are positively moved into engagement with the driven fly wheel member, a ring loosely arranged on the hub of said driving member, a pair of links pivotally connected at one of their ends to said ring at diametrically opposite points and at their opposite ends to said control arms to effect simultaneous and uniform operation of said control arms.
- 20 9. A pair of coaxial fly wheel members rotatable independently of each other and adapted to be interengaged, each of said members being provided with obliquely disposed spokes spaced unevenly with respect to the spokes of the other fly wheel member so that at no time can said fly wheel members become interengaged with all of the spoke openings of one member blocked by the spokes of the other member.
- 25 10. In a compressor for domestic refrigerating machines, the combination with the actuating shaft thereof, of a fly wheel driven member fixed thereto, a driving fly wheel member rotatable independently of said driven fly wheel member and mounted adjacent thereto, and means for engaging said fly wheel members together for actuating said shaft, the spokes of one fly wheel member being differentially spaced with respect to the spokes of the other fly wheel member 30 so that at no time can the air spaces between the spokes of one of the members be blocked by the spokes of the other member.
- 35 11. In a compressor for domestic refrigerating machines, the combination with a compressor shaft, of a driven fly wheel member fixed thereto, a driving fly wheel member loosely supported on said shaft and arranged adjacent to said driven fly wheel member, centrifugally operable means for interengaging said fly wheel members and actuating said shaft, auxiliary centrifugally operable means for engaging the first mentioned centrifugal means and holding the latter in retracted position for a definite 40 period of time after said fly wheel driving member has attained the speed necessary to actuate said first mentioned centrifugal means, said auxiliary means being operable at a greater speed than said first mentioned means to insure efficient interengagement between said fly wheel members, the spokes of each fly wheel member being angularly disposed to force the air in one direction, the spokes of one fly wheel member being 45 spaced in a definite relation with the spokes of the other fly wheel member to prevent blocking of all air spaces between the spokes by each other when said members are interengaged, thereby insuring efficient circulation of air through said fly wheel device.
- 50 In testimony whereof I hereunto affix my signature this 28 day of August, 1926.
- 55 JOHN O. CARREY.
